UNITED STATES PATENT OFFICE.

WILLIAM J. HESS, OF FORT WAYNE, INDIANA, ASSIGNOR TO VAN ARNAM MANUFACTURING COMPANY, A CORPORATION OF INDIANA.

HINGE FOR WATER-CLOSET SEATS AND COVERS.

Application filed November 13, 1926. Serial No. 148,178.

This invention relates to improvements in hinges for water closet seats and covers, and the objects thereof are to provide hinge support on a water closet bowl for the seat and cover therefor, which support presents only a small exposure to view, and to construct said support so as to be applied to a bowl having standards spaced post holes for the hinge support of a seat and cover, the rear ends of which are wider than the space between the post holes. An especial object of the invention is to provide a neat hinge support for the seat and cover without encumbrance thereto and which will be substantial and durable. Another object is to so construct the hinged support that it may be easily applied and fixedly secured without marring the seat and cover.

These objects are accomplished by the construction illustrated in the accompanying drawings, in which:—

Fig. 1 is a side elevation of a toilet seat and cover therefor with the hinge support applied thereto;

Fig. 2 is a plan view projected from Fig. 1, partially broken away;

Fig. 3 is a perspective view of one of the supporting posts applicable to the bowl;

Fig. 4 is a perspective view of one of the hinge members applicable to the seat; and

Fig. 5 is a perspective view of one of the posts applicable to the seat for the support of the cover.

The characters appearing in the description refer to parts shown in the drawings and designated thereon by corresponding characters.

The invention consists of a seat and cover therefor and a hinge support for mounting the seat and cover in connection with a water closet bowl (not shown).

The seat 1 has at its rear end an extending portion 3, and the cover 2 has at its rear end an extending portion 4, the extension on the cover being of less breadth than the extension on the seat so that the extension on the seat has an exposed portion 3' at each side thereof beyond the corresponding sides of the cover.

The hinge support consists of a pair of posts 5, each having at its upper end a head 6 with a horizontally disposed opening 7 therein, the posts being applicable to the bowl, in the spaced post holes therein, in the customary manner, there being provided

washers 8 and a nut 9 for securing each post in place. A pair of hinge members 10 are secured to the extended portion 3 of the seat upon the under side thereof, each hinge member having a laterally disposed trunnion 11 that projects into the opening 7 in the head of the corresponding post so as to have pivotal action therein. Each hinge member has also an integral wing 12 provided with a screw opening 13 therein and an upwardly projecting stud 14. The wings 12 of said hinge members are so formed that when said members are operably connected with said posts, the wings spread outwardly from each other to such an extent that their screw openings 13 are disposed respectively at points beyond the corresponding sides of the extension 4 of the cover 2. Upon each of the exposed portions 3' of the extension of the seat is positioned a post 15 having a horizontally disposed opening 16 therein, said post being secured in position on said extension by a corresponding screw 17 that constitutes also the means for securing the corresponding hinged member to said extension. Said screw 17 extends through the wing 12 of the corresponding hinge member through the screw opening 13 therein, and projects upwardly through the extension 3 in the seat and has threaded engagement with the corresponding post 15. The stud 14 on the wing of the hinge member projects into the seat and serves to prevent the hinge member from having turning movement relative to the seat. A pintle 18 is positioned in each side of the cover in the extension thereof, with its outer end projecting into the opening 16 in the corresponding post 15, so that the cover has hinge movement between the post 15 on the seat while the seat has hinge movement relative to the main supporting posts 5.

By thus constructing the invention each hinge member and corresponding post 15 for the cover are both substantially secured to the seat by a single screw. By forming the wings of the hinge members so as to spread outwardly from each other, and spacing the posts 15 correspondingly, the width of the extension 4 on the cover is not reduced to such an extent as to impair its strength or the beauty of its design.

What I claim is:—

1. In combination with a water closet seat and cover therefor, a pair of hinge posts; a

- pair of wings hinged respectively in connection with said posts and extending beneath said seat; superimposed posts on said seat pivotally supporting said cover; and a screw 5 connecting each of said wings and the corresponding superimposed post through said seat, there being a stud on each wing projecting into said seat to prevent displacement of said wing.
10. 2. In combination with a water closet seat and cover therefor, a main supporting hinge member comprising a post and wing pivoted thereon, said wing being secured to said seat; a superimposed post on said seat pivotally connected with said cover; and a screw 15 extending through said seat connecting said wing and superimposed post.
15. 3. In combination with a water closet seat

and cover therefor, a hinge supporting said seat attached therebeneath; and another 20 hinge superimposed upon the seat supporting said cover, said hinges being connected together through said seat.

4. A water closet seat and cover therefor, each having a rearwardly extending portion, 25 the extending portion of said seat having an exposed area at each side of the seat beyond the corresponding side of said cover; a hinge post superimposed upon each of said exposed areas pivotally supporting said 30 cover; hinges for the seat attached thereunder beneath the posts thereon; and means extending through said seat connecting said hinges and corresponding posts.

In testimony whereof I affix my signature.
WILLIAM J. HESS.
